Primary Examiner — Derrick Holland*Assistant Examiner* — Lauren Calve(74) *Attorney, Agent, or Firm* — Muncy, Geissler, Olds & Lowe, P.C.(57) **CLAIM**

I claim the ornamental design for a toolbox handle, as shown and described.

DESCRIPTION

FIG. 1 is a right, front, top perspective view of a toolbox handle showing my new design;

FIG. 2 is a front elevational view thereof, the rear being a mirror image;

FIG. 3 is a left side view thereof, the right side being a mirror image;

FIG. 4 is a top plan view thereof;

FIG. 5 is a bottom plan view thereof;

FIG. 6 is a cross-sectional view thereof, taken along lines 6-6 shown in FIG. 2;

FIG. 7 is a second right, front, top perspective view thereof; and,

FIG. 8 is a perspective view thereof shown in environmental use.

The broken lines shown represent unclaimed subject matter and form no part of the claimed design.
